DESIGN FOR A COMBINED SHOE TREE AND SHOEHORN

Albert G. Berry, Jr., Beverly Hills, Calif.

Application August 15, 1944, Serial No. 114,893

Term of patent 14 years

(Cl. D7—3)

To all whom it may concern:

Be it known that I, Albert G. Berry, Jr., a citizen of the United States, residing at Beverly Hills, in the county of Los Angeles and State of California, have invented a new, original, and ornamental Design for a Combined Shoe Tree and Shoehorn, of which the following is a specification, reference being had to the accompanying drawing, forming part thereof.

Fig. 1 is a top plan view;

Fig. 2 is a side elevational view;
Fig. 3 is a bottom plan view;
Fig. 4 is a front elevational view; and
Fig. 5 is a rear elevational view of a combined
shoe tree and shoehorn showing my new design.

I claim:

The ornamental design for a combined shoe
tree and shoehorn, as shown.

ALBERT G. BERRY, JR.
